CLAIM

The ornamental design for an in-ear device, as shown and described.

DESCRIPTION

FIG. 1 is a top perspective view of an in-ear device of the new design;

FIG. 2 is a front elevational view thereof;

FIG. 3 is a left side elevational view thereof;

FIG. 4 is a right side elevational view thereof;

FIG. 5 is a bottom plan view thereof; and,

FIG. 6 is a top plan view thereof.

In all Figures, the broken lines representing environmental structures are for illustrative purposes only and do not form part of the design.
